BUCKLE

Jacob I. Schaffer, Bronx, N. Y.

Application January 6, 1933. Serial No. 650,483

5 Claims. (Cl. 24—163)

This invention pertains to buckles, particularly such as are employed, for example, for fastening belts or other articles of wearing apparel, although the invention is applicable to buckles of general utility, the invention relating particularly to an improved ratchet device for use in such buckles.

One common practice in making buckled belts, particularly for women's wear, is to sew one end of the belt material to the buckle, but, although belts are made in various standard lengths, the retail dealer is constantly confronted with the necessity of cutting belts down to the exact length demanded by the individual customer, and this necessitates removal of the buckle,—cutting off a portion of the belt, and re-sewing it to the buckle, all of which takes time, and unless great care is exercised in making the requisite measurements with proper allowance for doubling and sewing, the re-sized belts may still be found of improper length.

To avoid this sewing operation it has been proposed to make buckles with releasable clamping or "ratchet" devices for holding the end of the belt. However, such ratchet devices as usually made have no provision for guiding the operator in so repositioning the end of the belt (after it has been cut) that the clamping element will engage the belt at the proper point in its length. Moreover, such ratchet devices are thick and expose a corner or angle toward the wearer's body; the arrangement of parts is such that the belt tends to press the angle of the ratchet device against the wearer with uncomfortable pressure, at the same time tending to throw the buckle outwardly at an angle and give it undue prominence; the raw or unfinished end edge of the belt is partially exposed so that, if it tends to ravel or fray, the ravelings are exposed to view,—while the general appearance of the ratchet, at least from the rear side, is crude and clumsy.

The principal objects of the present invention are to provide a buckle ratchet wherein the above-noted disadvantages of prior constructions are avoided, and, in particular, to provide a ratchet applicable to buckles of various kinds, including center bar buckles, which is of dainty and neat appearance and but little thicker than the thickness of the belt material; which has a gauge and guard for the raw end edge of the belt fabric, whereby the position of such edge is accurately determined while at the same time such edge is protected and concealed;—which has a substantially smooth back adapted to lie substantially flat against the wearer's body without tipping the

buckle or producing undue or uncomfortable pressure; which is of pleasing appearance both at the front and back;—wherein the clamping lever is readily accessible and easily actuatable; and which may be made rapidly and by simple and inexpensive methods.

In the accompanying drawing wherein one desirable embodiment of the invention has been illustrated by way of example, as applied to buckles of different types;—

Fig. 1 is a front elevation of a center bar buckle embodying the present invention, the buckle being shown as attached to a belt;

Fig. 2 is an edge elevation of the buckle shown in Fig. 1;

Fig. 3 is a rear elevation, to larger scale, illustrating the buckle ratchet forming the immediate subject matter of the present invention, shown with its parts in belt clamping position;

Fig. 4 is a view similar to Fig. 3, but showing the clamp elements released;

Fig. 5 is a front elevation of the device shown in Fig. 3;

Fig. 6 is a section substantially on the line 6—6 of Fig. 5;

Fig. 7 is an end elevational view looking from the right-hand side of Fig. 5 and showing the clamping means released;

Fig. 8 is a rear view illustrating the invention as applied to a different form of buckle, the two parts of the buckle being separated; and

Fig. 9 is an edge elevation of the device shown in Fig. 8, but with the two parts of the buckle united.

Referring to the drawing, the numeral 1 designates the front member of a center bar buckle, said member having the center bar 2 which supports the usual tongue 3 adapted to engage the openings in the free end 4 of a belt whose other end 5 is attached to the buckle by means of the ratchet device 6.

This improved ratchet device which forms the subject matter of the present invention preferably consists, except for the movable clamping member, of a single unitary piece of sheet metal bent to the desired shape.

Referring more particularly to Figs. 3 to 7, the ratchet device 6 comprises a front wall 7 (Fig. 5) which is preferably substantially flat and smooth;—end walls 8 and 9;—a rear wall 10 comprising the spaced fixed parts 10 and 11 disposed adjacent to the opposite end walls 8 and 9, respectively; and extensions 12 and 13 lying substantially in the same plane as the rear wall members 10 and 11, respectively, and having their

end portions bent to form the hooks 14 and 15. The ratchet device also comprises the stop or gauge wall 16, here shown as projecting at right angles to the wall 7 and extending substantially 5 to the rear wall members 10 and 11;—the parts 12 and 13 projecting outwardly beyond and overlapping the free edge of the wall member 16.

The end walls 8 and 9 are furnished with bearing 10 openings 17 for the reception of pintle members 18 projecting from opposite edges of the clamping device and forming a pivotal support for the latter. This clamping device comprises the member 19 which normally lies substantially 15 in the plane of the members 10 and 11 (Fig. 3) and the members 10, 11 and 19 form parts of the rear wall of the ratchet. The clamping device also has a portion 20 disposed substantially at right angles to the part 19, such portion 20 preferably having a toothed edge for engagement with 20 the belt material.

Preferably the members 10 and 11 have oblique 25 edges 21 and 22, respectively, and the part 19 has corresponding edges 23 and 24, so that when the clamping device is in operative position, the part 19 may lie substantially in the plane of the parts 10 and 11, as above described, providing a smooth and substantially flat rear wall parallel 30 to the front wall 7, and together with the side walls 8 and 9 and the gauge wall 16 constituting a housing for the end of the belt. Preferably the member 19 has an edge portion 25 which is adapted to overlap the edge of the wall 16 to a slight extent (Figs. 3 and 6) when the parts are in clamping position, thus furnishing a finger 35 engaging portion, located between adjacent edges of the members 12 and 13, for engagement by the finger of the operator when he desires to release the belt from the ratchet device.

When this ratchet device is to be employed with 40 a center bar buckle, the hooks 14 and 15 are engaged with the center bar 2 and then bent over, as shown at 14^a, 15^a (Figs. 1 and 2) so as permanently but pivotally to unite the ratchet device with the front member 1 of the buckle.

In using the device, the member 19 is swung 45 downwardly, as shown for example in Fig. 7, and the end of the belt material is introduced between the inner surface of the front wall 7 and the member 20, which is now spaced to a maximum 50 extent from the front wall. The end edge of the belt material is now pushed inwardly until it comes into engagement with the gauge wall 16 which limits further movement, thus positively determining the amount of the belt material which 55 may project beyond the clamping device 20. The member 19 is then swung into its operative position (Figs. 3 and 6), at the same time carrying the member 20 up into a position such as to clamp the end 5 of the belt firmly against the inner surface of the front wall 6, it being noted that in this position of the parts the rear flat wall of the housing is substantially parallel to the belt so that strain put upon the belt has little, if any, tendency to tip the ratchet device toward or away 60 from the wearer's body.

When the end of the belt is thus clamped in position, its end edge (which may be raw or unfinished as a result of cutting the belt material to the desired length) is concealed and protected 65 so that it cannot ravel out or otherwise exhibit an unsightly appearance. Since it is not necessary to double back any portion of the belt when it is introduced into the ratchet device,—the belt may be cut to the desired length without difficulty, and by reason of the limit abutment or gauge 70 16,

may be placed in the proper position for clamping without any substantial care or the exercise of skill on the part of the operator.

In the arrangement shown in Figs. 8 and 9 the ratchet device 6 is substantially as shown in the previous figures, with the exception that the hook members 14 and 15 are not bent downwardly but are left in their open position. In this instance the opposite end 4^a of the belt is provided with a suitable ratchet device 6^a which, if desired, may be substantially similar to the ratchet device already described, except that in place of the hooks 14 and 15 it may be furnished with slots 26 and 27 in its extension members 12 and 13 for the reception of the hooks 14 and 15, respectively. 80 85 90

It will be noted that the improved ratchet device provides a substantially flat rear surface which is neat in appearance, which does not present any angles such as might cause discomfort to the wearer; that it is thin in a front to rear direction so that it occupies but little space; that a belt may be readily introduced and clamped or released, when desired, for readjustment or resizing; and that at the same time the device is of very simple construction and may be made 100 cheaply and rapidly by the use of automatic machinery.

While I have illustrated one desirable embodiment of the invention, together with certain applications thereof, I wish it to be understood 105 that these illustrations are merely by way of example, and that the invention in its broader aspects is capable of embodiment in other specific constructions, and that all such modifications and equivalents as fall within the scope of the 110 appended claims are to be regarded as within the purview of my invention.

I claim:

1. A buckle ratchet comprising a piece of sheet metal having a substantially flat front member 115 constituting a support for one face of the end portion of a belt, a wall projecting rearwardly from one edge of the front member substantially at right angles to said support and adapted to cover and conceal the end edge of the belt, end 120 walls projecting rearwardly from said front member, a clamp pivotally supported by said end walls, said clamp having a part adapted to engage the rear surface of the belt and to press the belt against the support, and a clamp actuating lever normally parallel to the support and overlying the rear surface of the belt, said lever normally contacting with the rear edge of said wall, the lever projecting beyond said wall to provide a finger-engaging element. 125 130

2. A buckle ratchet comprising a box-like housing having substantially parallel front and rear walls spaced to receive a belt end between them, a wall adapted to conceal and protect the end edge of the belt, and end walls for confining 135 the belt laterally within the housing, the rear wall having hook-like continuations for engagement with another buckle member, and also comprising a pivoted portion constituting an actuating lever, and a clamp secured to said lever 140 for actuation thereby to press the belt into contact with the front wall of the housing.

3. A buckle ratchet comprising a housing for a belt end, said housing having substantially parallel front and rear walls spaced to receive 145 a belt end between them, and a stop wall extending from the front wall substantially to the rear wall for determining the position of the end edge of the belt, the rear wall comprising fixed portions adjacent to opposite ends of the 150

- housing, said fixed portions having diagonal edges, the rear wall also comprising a pivotally supported portion having diagonal edges adapted to abut the diagonal edges of the fixed portions, 5 and a clamp element secured to said pivoted portion, the latter constituting an actuating lever for the clamp element.
4. A buckle ratchet comprising a housing for a belt end, said housing having substantially 10 parallel front and rear walls spaced to receive a belt end between them, and a stop member projecting from one of said walls toward the other for determining the position of the end edge of the belt, the rear wall comprising spaced 15 fixed parts and a pivoted part, the pivoted part having an edge normally overhanging the stop member at a point between said fixed parts to provide a finger-engaging element, and a clamp secured to the pivoted part of the rear wall, said pivoted part constituting an actuating lever for the clamp.
5. A buckle ratchet comprising a unitary piece of sheet metal bent to provide a substantially flat front member constituting a support for a belt end, a stop wall and end walls substantially perpendicular to said support, rear wall members substantially parallel to the support, said rear wall members overhanging the stop wall and having hook-like extensions, and a movable rear wall member pivotally supported by the end walls and normally disposed substantially in the plane of the fixed members of the rear wall, and a clamp secured to said movable rear wall member, the latter constituting a lever for moving the clamp to clamp the belt end against the support. 80 85 90
